(57) **CLAIM**

The ornamental design for an infant garment for mitigating plagioccephaly, as shown and described.

DESCRIPTION

FIG. 1 is a front perspective view of an embodiment of an infant garment for mitigating plagioccephaly;

FIG. 2 is a front view of the infant garment of FIG. 1;
FIG. 3 is a rear perspective view of the infant garment of FIG. 1;

FIG. 4 is a rear view of the infant garment of FIG. 1;

FIG. 5 is a first side view of the infant garment of FIG. 1;

FIG. 6 is a second side view of the infant garment of FIG. 1;

FIG. 7 is a top view of the infant garment of FIG. 1;

FIG. 8 is a bottom view of the infant garment of FIG. 1;

FIG. 9 is a front perspective view of another embodiment of an infant garment for mitigating plagioccephaly;

FIG. 10 is another front view of the infant garments of FIGS. 1 through 9 with one portion of an adjustable waistband on one lateral side in a fixed, adjusted position and another portion of the adjustable waistband on another lateral side in a movable, adjustable position;

FIG. 11 is a still further front view of one of the portions of the adjustable waistband of FIG. 10 in the movable, adjustable position;

FIG. 12 is an enlarged view of the adjustable waistband within the area labeled 12 of FIG. 10; and,

FIG. 13 is an enlarged view of the adjustable waistband within the area labeled 13 of FIG. 11.

The infant wearing the garment and depicted in broken lines throughout the figure views is for illustrative purposes in showing the design in a condition of use and forms no part of the claimed design. The lighter weight broken lines, both on the claimed surface and beyond the boundaries of the claimed design, depict portions of the infant garment that form no part of the claimed design. The heavier weight broken lines upon the claimed surface (along the perimeters of the snap closure tabs and within the upper and side perimeters of the sleeve inserts on the back) show stitching that forms no part of the claimed design. On the arms and legs of the garment, the dot-dash lines in the first embodiment and consistent length broken line edges of the garment in the second embodiment are boundaries of the claimed design and form no part of the claimed design. The dashed line rectangles in FIGS. 10 through 13 show the boundaries of the enlarged views and also form no part of the claimed design.
